DESIGN FOR A TRAILER

Irving H. Judd, Detroit, Mich., assignor to Whitehead & Kales Company, River Rouge, Mich., a corporation of Michigan

Application February 14, 1934, Serial No. 50,731

Term of patent 14 years

To all whom it may concern:

Be it known that I, IRVING H. JUDD, a citizen of the United States of America, residing at the city of Detroit, in the county of Wayne, in the State of Michigan, have invented a new, original, and ornamental Design for a Trailer, of which the following is a specification, reference being had therein to the accompanying drawings forming a part thereof, wherein:

I claim:

The ornamental design for a trailer substantially as shown.

IRVING H. JUDD.
